Des. 179,588
Patented Jan. 29, 1957

179,588

CHILD'S SOCK

Janice M. Beaver, Cedar Grove, N. J.

Application November 4, 1955, Serial No. 38,724

Term of patent 14 years

(Cl. D47—7)

FIG. 1

FIG. 2

Fig. 1 is a front view of a child's sock embodying my design; and

Fig. 2 is a rear view thereof.

I claim:

The ornamental design for a child's sock, as shown.
